*Primary Examiner—Philip S. Hyder**Assistant Examiner—Adir Aronovich**Attorney, Agent, or Firm—Foley & Lardner*[57] **CLAIM**

The ornamental design for a viewing screen for a video camera, as shown and described.

DESCRIPTION

FIG. 1 is a perspective view of a viewing screen for a video camera showing my new design;

FIG. 2 is a perspective view thereof, the viewing screen is in the open position;

FIG. 3 is a top plan view thereof;

FIG. 4 is a front elevational view thereof;

FIG. 5 is a side elevational view thereof;

FIG. 6 is a bottom plan view thereof;

FIG. 7 is a rear elevational view thereof;

FIG. 8 is a top plan view thereof, the viewing screen shown in the open position;

FIG. 9 is a side elevational view thereof, the viewing screen shown in the open position;

FIG. 10 is a front elevational view thereof, the viewing screen shown in the open position;

FIG. 11 is a bottom plan view thereof, the viewing screen shown in the open position;

FIG. 12 is a rear elevational view thereof, the viewing screen shown in the open position;

FIG. 13 is a perspective view thereof, the viewing screen shown in the first alternate position;

FIG. 14 is a perspective view thereof, the viewing screen shown in the second alternate position;

FIG. 15 is a rear elevational view of a second embodiment of a viewing screen for a video camera, the viewing screen shown in the open position;

FIG. 16 is a perspective view of the second embodiment of the viewing screen for a video camera, the viewing screen shown in the open position; and,

FIG. 17 is a perspective view of the second embodiment of a viewing screen, the viewing screen shown in the first alternative position.

The undisclosed views of the second embodiment are identical to the views of the illustrated in the first embodiment. Video camera portions shown in broken lines are for illustrative purposes only and form no part of claimed design.
